UNITED STATES PATENT OFFICE.

JOSEPH COGOZZO, OF ROCHESTER, NEW YORK, ASSIGNOR TO AMERICAN PIANO COMPANY, OF NEW YORK, N. Y., A CORPORATION OF NEW JERSEY.

WIRE-TWISTING MACHINE.

1,310,003.

Specification of Letters Patent. Patented July 15, 1919.

Application filed June 10, 1916. Serial No. 102,852.

To all whom it may concern:

Be it known that I, JOSEPH Cogozzo, a citizen of the United States, residing at Rochester, in the county of Monroe, State 5 of New York, have invented an Improvement in Wire-Twisting Machines, of which the following is a specification.

This invention relates to improvements in machines for forming wire loops, particularly such loops as are usually formed at the ends of piano string wires for the purpose of fastening the strings to the hitch pins of a piano. The principal object of the invention is to provide a machine whereby 15 these loops may be formed most expeditiously, in a minimum of time, and by the use of as little wire as possible; thereby effecting a saving in material and labor.

The invention will be hereinafter described by reference to a machine showing a preferred embodiment of the invention.

In the accompanying drawings,

Figure 1 is a side elevation of a machine constructed in accordance with my invention;

Fig. 2 is an end elevation of the machine of Fig. 1; and

Figs. 3 to 9 inclusive are detail views of the jaws of the machine of Fig. 1, and illustrating several stages in the formation of the loop.

In the formation of the loop a portion of the piano string wire is first bent back upon itself to form an open loop having two substantially parallel runs. The open loop so formed is then placed over a twisting hook or other suitable device to impart, at the proper time, a rotary motion to the looped end of the wire. It is desired to twist together the parallel runs of the piano string wire for some distance from the end, thus forming a closed loop, and thereafter to coil a portion of the free end of the piano string wire about the main run of the wire 45 to complete the formation of the finished loop. For the proper engagement of the parallel runs of the open loop and for the proper guidance of the wire in the formation of the twisted and coiled parts of the completed loop, a pair of coöperating jaws are herein provided, the construction and arrangement of which will be hereinafter more fully described.

In the present embodiment of the inven-

tion a jaw 1 is shown as being mounted in 55 fixed position upon a forwardly extending bracket or anvil 3 of a base 4 of the machine. A coöperating jaw 2 is herein shown as movable relatively to the jaw 1. Means are provided for moving the jaw 2 toward 60 or away from the jaw 1, the same being herein shown as a lever 5, to which the jaw 2 is attached at its outer end, fulcrumed at 6 in a lug 7 extending upwardly and rearwardly from the base 4. It will thus be seen 65 that the rotation of the lever 5 about its fulcrum in a clockwise direction, will, if continued far enough, cause the jaws 1 and 2 to engage each other and to hold firmly any material which may be placed therebetween. 70

Means may be provided for operating the jaw carrying lever 5, the same being herein shown as a connecting rod 8 mounted upon a rock shaft 9 which is journaled between a pair of arms 10 rigidly secured to the base 75 4 and extending rearwardly therefrom. The connecting rod is connected by suitable means to the lever 5, herein shown as a link 11 pivoted to the lever 5 at 12 and adjustably secured to an eccentric collar 32 by 80 means of a screw-threaded stud bolt 13. It will thus be apparent that upon the rotation of the shaft 9 from the position shown in the drawings, the jaws 1 and 2 will be brought together, and that upon the return of the 85 shaft 9 to the position shown, the jaws will be separated one from the other. As a convenient means for operating the shaft 9 a handle 14, extending toward the front of the machine, is provided.

Any practicable mechanism may be employed to position a twisting hook 15 in proper relation to the jaws 1 and 2 and preferably the twisting hook is attached to a machine which will automatically, upon 95 the release of suitable clutch mechanism, rotate the hook through any number of desired revolutions. Such mechanism is well known in the art and, therefore, is not herein described or shown.

The jaws 1 and 2 are preferably so formed that they will provide suitable guides for properly positioning the main run of the piano string wire and for forming a right angle bend in the wire automatically upon 100 being brought together, prior to the twisting of the wire by the hook 15. The particular form of jaw herein shown for the

purpose of illustration, in the case of the lower jaw 2, comprises a rectangular body portion 16 (see Figs. 3 and 4) having a projection 17 integral therewith and extending 5 upwardly therefrom. The upwardly projecting extension 17 is preferably provided with a stop wall 18 extending substantially thereabove and a slight depression or groove 19 may be formed in the upper surface of 10 the projection 17 closely adjacent the stop wall 18, for the purpose of guiding the shorter parallel run of the wire prior to the formation of the closed loop. Preferably the forward edge of the projection 17 is 15 slightly rounded or beveled as shown, for the purpose of forming the right angle bend in the short parallel run of wire. Also rising from the base 16 of the jaw 2 is a stop 20 lying along the opposite edge of the base 20 16 and adapted to form, in coöperation with the adjacent wall of the stop 17, a guideway for the main run of the piano string wire. In the base 16, adjacent and in front of the projection 17 is a groove 21, which will be 25 later referred to.

The coöperating movable jaw member 2 comprises a substantially rectangular body portion having a front wall 22 and a stop wall 23 and formed with a recess to receive 30 the upwardly extending stop portion 20 of the lower jaw 1. A depending flange 24 is provided to fit into the space between the stop 20 and the projection 17 of the lower jaw when the jaws are brought together. In 35 the front wall 22 of the upper jaw may be located a vertically disposed groove 25 substantially in alignment with the inner face of the upwardly extending stop wall 18 of the jaw 1. The purpose and functions of 40 this groove together with a notch 26 formed in the lower face of the flange 24 will be later described.

The completed loop is shown in Fig. 9 and therein the main length of the wire is indicated by the numeral 27, the loop by the numeral 28, the shorter parallel run by the numeral 29, and that portion of the wire which is coiled upon the main length of wire by the numeral 30. This figure shows 45 a preferred form of completed loop and it will be seen that therein the portions 27 and 29 of the wire have been twisted upon each other from the loop to a point adjacent the edge of the jaw member shown in that figure, and that thereafter the portion 30 has been coiled upon the portion 27. These 50 parts of the wire are correspondingly numbered throughout the preceding figures and in the description of the operation of the 55 apparatus will be so referred to.

In the operation of the above described machine in accordance with the method herein disclosed, the machine is mounted, preferably, at a considerable distance from 60 a support for a supply of piano string wire.

A portion of the leading end of the wire, of sufficient length to form the twisted and coiled portions, is bent back upon the main or standing part of the wire thereby forming a bight or open loop. The open loop so 70 formed is placed over the twisting hook 15 as shown in Fig. 3 so that the standing portion of the wire 27 lies in the guide space between the side wall of the projection 17 and the inner wall of the projection 20. 75 The shorter run 29 of the wire is disposed along the outer face of the flange 18 to lie partially within the groove 19. The coöperating jaws and the wire are then substantially in the position shown in Fig. 4 of the 80 drawings.

Thereupon the handle 14 is rotated to bring the upper jaw 2 down upon the lower jaw. The inner corner of the portion 22 of the upper jaw 2 will then engage the shorter 85 run 29 of the wire substantially as shown in Fig. 5 and will operate to form a right-angled bent-up portion 30 which will lie substantially within the groove 25 when the jaws have been brought fully together. 90 Upon the further movement of the handle 14 the two substantially parallel runs of wire 29 and 27 will be firmly clamped between upper jaw member 22 and lower jaw member 16. Thereupon the twisting mechanism is operated, preferably about four revolutions, to 95 twist one run of the wire with the other and the result will be substantially that shown in Fig. 6.

The two runs 29 and 27 having thus been 100 twisted together the handle 14 is moved slightly toward its former position thus separating the two jaws and releasing the pressure upon the parallel runs of wire. The tension of the twisted wire will thereupon cause the right angular bent-up portion 30 to snap down and engage the abutment 16 of the lower jaw member substantially along the guiding groove 21 as shown in Figs. 7 and 8. The jaw member 2 is 110 then brought down to bear lightly against the two wires in this position and the twisting hook 15 is further rotated. Upon the rotation of the twisting hook as last described the entire length of wire from the 115 hook to the main supply of wire will be twisted upon itself, thus imparting a rotation to that portion of the main length of wire held loosely between the jaws 1 and 2. This rotation of the portion of the wire thus 120 lightly engaged by the jaws will operate to coil the right angular bent-up portion 30 about the main or standing length of wire 27 in the manner shown in Fig. 9. The portion of the wire 30 lying along the groove 125 21 will be guided thereby and by the notch 26 so that it will be neatly coiled upon the main run 27. This second rotation of the twisting hook may be continued long enough 130 to coil the entire end 30 around the main

run 27 and thus obviate the necessity for cutting off and thereby wasting any portion of the wire.

It will be understood that the present invention as it relates to the machine may be variously modified and embodied within the scope of the subjoined claims.

I claim as my invention:

1. A device of the character described comprising a rotatable wire-twisting member; a wire-receiving member having means to clamp the wire in a line with the axis of rotation thereof; and an abutment extending from said line and substantially co-planar therewith to resist revolution about said axis of wire portions not substantially co-linear therewith.
2. A device of the character described comprising a rotatable wire-twisting member; a wire-receiving member having means to clamp the wire in a line with the axis of rotation thereof; an abutment extending from said line and substantially co-planar therewith to resist revolution about said axis of wire portions not substantially co-linear therewith; and guiding means coöperating with said abutment to maintain the direction of the wire portions so disposed.
3. A device of the character described comprising a rotatable wire-twisting member and a wire-receiving member comprising jaws releasably to clamp a doubled wire substantially in a line with the axis of rotation of said wire-twisting member, said jaws embodying a wire-bending mechanism to deflect a portion of wire from said line and an abutment extending from said line and substantially co-planar therewith to resist revolution of said portion about said axis.
4. A device of the character described comprising a rotatable wire-twisting member and a wire-receiving member comprising jaws to clamp a doubled wire substantially in a line with the axis of rotation of said wire-twisting member, said jaws embodying a wire-bending mechanism to deflect a portion of wire from said line and an abutment extending from said line and substantially co-

planar therewith to resist revolution of said portion about said axis, and guiding means 50 coöperating with said abutment to maintain the angular relation of the deflected portion to said axis.

5. A wire-receiving member for a wire-twisting mechanism comprising means releasably to clamp a doubled length of the wire against rotation about its longitudinal axis and an abutment to resist revolution about said axis of a portion of the wire disposed transversely to said axis, and guiding 60 means associated with said abutment to maintain the angular relation to said axis of a portion of the wire so disposed.

6. A wire-receiving member for a wire-twisting mechanism comprising means releasably to clamp a doubled length of the wire against rotation about its longitudinal axis and an abutment to resist revolution about said axis of a portion of the wire disposed transversely to said axis.

7. A wire-receiving member for a wire-twisting mechanism comprising jaws releasably to clamp a doubled wire against rotation about its longitudinal axis, said jaws embodying a wire-bending mechanism to deflect a portion of wire to a position transverse to said axis and an abutment to resist revolution about said axis of said deflected portion of the wire.

8. A wire-receiving member for a wire-twisting mechanism comprising jaws releasably to clamp a doubled wire against rotation about its longitudinal axis, said jaws embodying a wire-bending mechanism to deflect a portion of wire to a position transverse to said axis, an abutment to resist revolution about said axis of said deflected portion of the wire, and guiding means co-operating with said abutment to maintain the angular relation of the deflected portion 90 to said axis.

In testimony whereof, I have signed my name to this specification this sixth day of June, 1916.

JOSEPH COGOZZO.
